UNITED STATES PATENT OFFICE

136,022

DESIGN FOR A COMBINATION PARING KNIFE AND MEASURING SPOON

Solomon Barr Phillips, Waterbury, Conn.

Application May 6, 1943, Serial No. 110,137

Term of patent 7 years

To all whom it may concern:

Be it known that I, Solomon Barr Phillips, a citizen of the United States, residing in the city of Waterbury, county of New Haven, and State of Connecticut, have invented a new, original, and ornamental Design for a Combination Paring Knife and Measuring Spoon, of which the following is a specification, reference being had to the accompanying drawing forming a part thereof, in which:

Fig. 1 is a plan view of my new design of a combination paring knife and measuring spoon;

Fig. 2 is a side view thereof; and

Fig. 3 is a transverse cross-sectional view taken through the central handle of the design in order to more effectively show the recessed character of the handle.

I claim:

The ornamental design for a combination paring knife and measuring spoon, as shown.

SOLOMON BARR PHILLIPS.
